UNITED STATES PATENT OFFICE.

AUGUSTE NAMUR, OF NEW YORK, N. Y., ASSIGNOR TO THE TUTTLE & BAILEY MANUFACTURING COMPANY, OF SAME PLACE.

DESIGN FOR A HOT-AIR-REGISTER FRONT.

SPECIFICATION forming part of Design No. 16,059, dated April 21, 1885.

Application filed February 16, 1885. Term of patent 14 years.

To all whom it may concern:

Be it known that I, AUGUSTE NAMUR, a citizen of Luxemburg, residing at New York city, in the county and State of New York, have invented and produced a new and original Design for a Hot-Air-Register Front, of which the following is a specification.

The accompanying print is a front elevation of my newly-invented design for a hot-air-register front, in which the central portion consists of open fret-work composed of arches *a* *b* and sectional arches *a'* *b'*, supporting the radial flower figures *c*. The upper arch, *b*, rests on parallel supports *b'*, which extend down the sides of the center portion of the fret-work, and, together with lower arch, *b*, rest on the cross-bar *j*. The outer portion of said fret-work consists of the wheel figures *d*, corner figures, *e*, and the balustrade *f*, and these are surrounded by a border of point figures *g* on the stipple or dead finish of the frame *h*, and radiating from the inner marginal rib, *i*, of the frame.

I claim—

1. In a design for a hot-air-register front herein shown, the center portion of the open fret-work consisting of the arches *a* *b*, sectional arches *a'* *b'*, radial flower figures *c*, supports *b'*, supporting-bar *j*, and the open fret-work consisting of the wheel figures *d*, corner figures, *e*, and the balustrade *f*, as set forth. 25

2. In a design for a hot-air-register front herein shown, the center portion of the open fret-work consisting of the arches *a* *b*, sectional arches *a'* *b'*, radial flower figures *c*, supports *b'*, the open fret-work consisting of the wheel figures *d* and the balustrade *f*, and the border surrounding the open fret-work consisting of the point figures *g* on the frame *h*, radiating from the inner marginal rib, *i*, of 30 35 40 said frame, as set forth.

In witness whereof I have hereunto signed my name in the presence of two subscribing witnesses.

AUGUSTE NAMUR.

Witnesses:

W. J. MORGAN,
S. H. MORGAN.
